UNITED STATES PATENT OFFICE.

JULIUS A. SCHWANTES, OF MILWAUKEE, WISCONSIN, ASSIGNOR TO THE PALMOLIVE COMPANY, OF MILWAUKEE, WISCONSIN, A CORPORATION OF WISCONSIN.

APPARATUS FOR CUTTING SOAP INTO BARS.

Application filed April 3, 1922. Serial No. 549,313.

To all whom it may concern:

Be it known that I, JULIUS A. SCHWANTES, a citizen of the United States, and resident of Milwaukee, in the county of Milwaukee, 5 and State of Wisconsin, have invented new and useful Improvements in Apparatus for Cutting Soap into Bars, of which the following is a description, reference being had to the accompanying drawings, which are a 10 part of this specification.

This invention relates to an electrically operated device for cutting soap into bars which is preliminary to a further operation whereby they are cut into cakes.

15 This invention has for its object to provide a device of this type which will automatically sever the continuous bar of soap fed through the device into pieces of the proper length, the device being furthermore 20 capable of adjustment whereby the length of the pieces cut may be varied within certain limits.

With this object in mind the invention consists in the novel construction and arrangement of parts which will hereinafter 25 be more fully described and illustrated.

In the drawings—

Figure 1 is a side elevation of a portion of a machine for forming the soap in a continuous rectangular bar, with this improved 30 invention attached thereto.

Fig. 2 is an end view of the attachment.

Fig. 3 is an enlarged longitudinal section taken on the plane indicated by line 3—3 of 35 Fig. 2.

Fig. 4 is a diagrammatic view of the electrical connections employed.

Referring now more particularly to the drawings wherein like reference characters 40 represent like parts, the reference character 10 designates a portion of a machine for forming the soap into a continuous rectangular bar, which is ejected from the end thereof onto the support composed of rollers 11.

45 Referring to Fig. 2 wherein the discharge opening of the machine 10 is indicated by the reference character 12, the position of the device forming the subject matter of this present invention will be disclosed. Secured

adjacent the discharge opening 12 (see also Fig. 3) is a frame 13 provided with bearing members 14 which slidably support bars 15. Also secured to the machine 10 are two solenoids 16 provided with iron cores 17, the 55 windings of the solenoid being indicated at 18. The iron cores 17 are extended through the end of the solenoid 16 and have mounted thereon coiled springs 19 which engage on one hand against the end of the solenoid 16, 60 and on the other hand against a cap or the like 20 secured to the outer end of the core 17.

The other end of each core 17 is provided with a head 21 formed with an inclined bearing surface which engages a roller 22 rotatably mounted on the adjacent end of the bar 15. A spring 23 connected respectively to the core 17 and the bar 15 keeps the roller 22 in engagement with the head 21. 70

To the end of each bar 15 adjacent the discharge opening 12 of the soap machine there is pivotally journaled a knife 24, the pivot shaft of which carries a coiled spring 25 which tends to hold the knife 24 in the position illustrated in Fig. 3, that is in engagement with a projection 26 formed on the bar 15. The pivoted knives when operated function to sever the continuous bar of soap into pieces of the proper length and inasmuch as 75 the bar is continuously fed out of the machine the pivoted knives 24 swing away from the projections 26 during the cutting operation, thereby failing to materially interrupt the ejection of the soap bar. 85

Disposed at the top and bottom of the discharge opening 12 and suitably journaled in the frame 13 are rollers 27, while vertically disposed rollers 28 also journaled in the frame 13 are positioned adjacent the sides of 90 the discharge opening 12, whereby the ejection of the bar of soap is facilitated.

The knives 24 will be drawn toward one another to sever the bar of soap into pieces of suitable length when the solenoid windings 18 are energized and the cores 17 longitudinally displaced. For accomplishing this there is provided a control device comprising a bar 29 pivoted to the arm 30 at 31. This bar carries a stationary contact 32 en- 100

gageable by a contact 33 carried by a pivoted arm 34. The pivoted arm 34 projects upwardly into the path of the bar of soap S. A coiled spring 35 maintains the pivoted arm 34 in its spaced position. The lower end of the pivoted bar 29 has a sliding contact, as at 36, with a terminal member 37 to which one of the circuit wires 38 is connected. The circuit therefore is maintained 10 as long as the sliding contact 36 engages the terminal member 37 and the circuit will be broken when this member slides off the end of the terminal member 37. The pivoted lever 29 is rocked by engagement of the 15 bar of soap with the arm 34 which projects into its path of travel. The other circuit wire is indicated by the reference character 39.

The switch members thus far described 20 are the auxiliary or supplemental switches and control the current to the main switch which is contained in the oil tank 40. The switch arm 41 pivoted therein is attracted by an electromagnet 42 whereupon the contacts 43 are closed, these contacts being immersed in oil. When the electromagnet 42 is energized and the contacts 43 closed the circuit to the solenoids 16 will be complete and the knives 24 moved to cut the bar of 25 soap. Connection with a suitable source of current may be controlled by a hand switch 44.

It will be noted that the pivoted bar 29 acts as a circuit maker and breaker for the 30 main switch in that the circuit to the main switch is first closed by the engagement of the contacts 32 and 33 and is thereafter broken when the sliding contact 36 moves off the terminal member 37. When the contact members 32 and 33 engage, the electromagnet 42 is energized and remains energized while the soap is being cut. When the contacts 36 and 37 are disengaged, the circuit to the magnet 42 is broken and hence 35 the springs are permitted to return the knives or blades to their original position. By providing means for energizing the magnet which holds the main switch closed, the operation of the knives does not depend solely upon a continued engagement 40 of the contacts 32 and 33.

For regulating the length of the pieces 45 of soap to be cut the arm 30 is adjustably supported in a bracket 45 depending from the machine. The adjusting bolt 46 threaded into the end of the arm 30 enables the same to be moved horizontally thereby positioning the arm 34 variable distances from the discharge opening 12 of the soap machine. Therefore, the time at which the end of the bar of soap engages the switch arm 34 may be regulated.

In practice after the bar of soap has been 50 cut into pieces of the desired length it is removed from the machine and cut into

smaller cakes by means of wire cutters. Obviously, therefore, the size of the pieces of soap cut by this device must be accurately gauged so that the smaller cakes cut by the wire cutters will be uniform. 70

While one constructional example of this invention is illustrated herein it is not intended to limit this invention to the details of construction shown, but reservation is hereby made to make such changes and 75 modifications as may come within the purview of the accompanying claims.

Having thus described the invention what is claimed is:

1. In a device of the class described, a 80 pair of reciprocating knives, electrically actuated means for reciprocating said knives, a double switch for controlling said electrical means, said double switch being operated by the material to be cut for successively completing and breaking the circuit including said electrical means. 85

2. In a device for successively severing a continuous bar of soap into pieces of uniform length, a pair of reciprocating knives, 90 solenoid means for reciprocating said knives, and a double switch engageable by the bar of soap for causing successively an energization and de-energization of said solenoids. 95

3. In a device for successively severing a continuous bar of soap into pieces of uniform length, a pair of knives, solenoid controlled means for reciprocating said knives, said knives being pivotally mounted to 100 swing with the soap as it progresses, an electric circuit including said solenoids, and means for closing said circuit embodying a pivoted contact arm disposed in the path of the bar of soap and operated thereby. 105

4. The combination with a machine of the class described, of a device for successively severing a continuous bar of soap into pieces of uniform length, said device comprising a pair of knives disposed adjacent the discharge end of said machine, bars pivotally supporting said knives, solenoids provided with extended cores, springs surrounding said cores for retaining the same in a retracted position, means connecting said cores to said bars, an electric circuit including said solenoids, and a pivoted contact bar provided with a pair of contacts and a sliding contact, an arm pivoted to said bar and projecting into the path of the bar of soap, said bar of soap functioning to close said pair of contacts and to thereafter rock said bar to disengage said sliding contact. 115

5. A device of the class described comprising a pair of knives, bars pivotally supporting said knives, solenoids provided with cores having extensions thereon, resilient means connecting said cores to said bars, an electric circuit including said solenoids, a pivoted contact bar, an adjustable arm 120

supporting said pivoted contact bar, a pair of contacts carried by said bar and a sliding contact carried by said bar, said bar being provided with a contact arm projecting into the path of the bar of soap, a main switch contained in an oil tank, an electromagnet for keeping said main switch closed, said contact bar and main switch being included in said circuit whereby said solenoids may be periodically energized, 10 and means for adjusting said arm.

5 In testimony whereof, I affix my signature.

JULIUS A. SCHWANTES.
